UNITED STATES PATENT OFFICE.

CHARLES C. GAMM, OF ST. PAUL, MINNESOTA, ASSIGNOR TO WALDORF PAPER PRODUCTS COMPANY, A CORPORATION OF MINNESOTA,

SEALING MACHINE FOR FIBER CONTAINERS.

Application filed October 31, 1924. Serial No. 747,034.

To all whom it may concern:

Be it known that I, CHARLES C. GAMM, a citizen of the United States, residing at St. Paul, in the county of Ramsey and State 5 of Minnesota, have invented new and useful Improvements in a Sealing Machine for Fiber Containers.

It is my object to facilitate sealing fiber containers, such as those constructed of 10 paper or straw board or equivalent material, and at the same time to insure complete sealing.

More particularly, it is my object to provide a machine adapted to be operated to 15 simultaneously fold, square and seal a plurality of securing flaps upon a rectangular container. This invention also includes certain other novel features of construction, which will be more fully pointed out in the 20 following specification and claims.

Referring to the accompanying drawings, which illustrate the best form of my device at present known to me, Figure 1 is a side elevation of my improved machine showing 25 a container in place upon the form; Fig. 2 is an end view of a container of the type upon which my device is adapted to operate; Fig. 3 is a fragmentary sectional view through the bottom of the container; Fig. 4 is a plan view of the machine with the table 30 top and form removed; Fig. 5 is a detail end view of the pedal and associated parts; Fig. 6 is a plan view of the pedal; Fig. 7 is a plan view of the table top and form; Fig. 8 is a side elevation of the central slide 35 and operating rod; and Fig. 9 is a detail perspective view of the clamp supporting plate, one of the bosses being broken away to show parts otherwise concealed.

40 My machine is provided with a frame having legs 10 connected by transverse members 11 and supporting a table 12. Mounted centrally upon the table 12 is a form 13 adapted to fit within a rectangular container or caddy 14 to be sealed. Formed integral with the several sides of the container 14 is a series of flaps 16 adapted to be folded over and be secured upon the bottom or outer surface of the panel 15. The form 50 13 has a plain upper surface adapted to support an end or bottom panel 15 of the container 14.

To simultaneously fold and seal the several flaps 16 upon the panel 15, I provide 55 four clamping plates 17, carried upon the

upper ends of arms 18. These arms 18 extend upward through apertures 19 (Fig. 7) in the table 12 and are pivotally supported beneath the table upon horizontal pins 20. As clearly shown in Fig. 1, each of the arms 60 18 is provided with a pair of hubs 21 through which a pin 20 passes. Extending downward from the hubs 21, the arms 18 are provided with bifurcated lower ends 22, which are joined by pins 23 to rods 24. The 65 rods 24 are adapted to actuate the arms 18 as hereinafter described. Substantially vertical squaring surfaces 25 are formed upon the arms 18 beneath the plates 17 for engagement with the lateral surfaces of the 70 container 14 when in place upon the form 13.

The pins 20 carrying the arms 18 extend through perforations in the ears 26, and said ears are formed integral with a series of sleeves or bosses 27, extending upward from 75 a plate 28 (Figs. 1 and 9). The several sleeves 27 and plate 28 are bored to receive four vertical rods 29, which are fixed at their upper ends in the table 12. Suitable nuts and washers on the lower ends of the 80 rods 29, afford abutments for coiled springs 30, which resiliently support the plate 28. Rigidly mounted upon the center of the square plate 28 is a vertical shaft 31 arranged with its upper end adjacent to the 85 bottom of the table 12. Upon this shaft 31 is a slide 32 formed with pairs of laterally projecting ears 33 and downwardly extending arms 34. These arms 34 project through slots 34a in the plate 28 and are joined beneath said plate to a pedal lever 35 by a link 36. Each of the several pairs of ears 33 are joined by one of the rods 24 with the bifurcated lower end of one of the clamp 90 arms 18. To render the lengths of the rods 24 adjustable, the heads, which are joined to the ends 22 of the arms 18, are made revolvable upon threaded ends 24a of said rods, as indicated in Fig. 4.

The pedal lever 35 is pivoted at one end 100 upon a horizontal shaft 37 extending between a pair of the legs 10, and the free end 38 of said pedal is supported by a coiled tension spring 39, which is fixed at its upper end upon the bottom of the table 12. The end 38 of the lever 35 may be depressed against the action of the spring 39, and when depressed to its fullest extent, is caught by a detent 40. This detent is pivoted at 105 41 upon a vertical projection 42 of the frame. 110

A triangular tooth on the detent 40, normally projects, so as to engage the upper surface of the pedal 35, but when the pedal is depressed, it strikes said tooth to swing 5 the detent out of its path.

Operation.

In operation, the container 14 to be sealed is placed upon the form 13 with the flaps 16 10 extended upward above the top of said form. The panel 15 is now laid upon the top of the form 13 and adhesive is applied to the margins of said panel or to the abutting surfaces of the flaps 16. The end 38 of the 15 pedal 35 may be depressed to simultaneously fold, square and seal the several flaps 16 upon the panel 15. When the lever 35 is depressed, the slide 32, being connected by the arms 34 and link 36 with said lever, is 20 drawn downward upon the central shaft 31, carrying the inner ends of the oblique connecting rods 24 therewith. As the inner ends of said rods are moved downward, the lower ends of the arms 18 are forced outward to pivot said arms upon the pins 20 and strike the flaps 16 with the inner ends of the plates 17. As the rods 24 approach the horizontal, the surfaces 25 strike the lateral surfaces of the container 14 and square the 25 same. Continued downward movement of the pedal lever 35 brings the ears 33 in contact with the upper surface of the plate 28 when further movement of the pedal depresses said plate against the action of the 30 springs 30. Downward movement of the plate 28 carries the arms 18 downward to firmly press the bottom of the plates 17 upon the flaps 16. At the lower end of the 35 pedal stroke, the detent 40 moves into engagement with the upper surface of said pedal to hold it in depressed position. Thus, the flaps 16 are clamped upon the panel 15, where they are held by the plates 17 until the adhesive has dried or set sufficiently to insure a proper seal. As will now be readily understood, the container 14 is released by striking the detent 40 out of engagement with the pedal 35 and allowing the springs 30 and 39 to return the arms 18 40 to open position shown in Fig. 1.

While I have illustrated a machine particularly adapted to seal a container or caddy having a substantially square end or bottom, it will be obvious that by minor 45 changes in form and proportions, the machine may be adapted to seal containers of other types. Any such change, is considered within the spirit of my invention.

Having described my invention what I 50 claim as new and desire to protect by Letters Patent is:

1. In a machine for sealing a container of the type having a pair of oppositely disposed flaps adapted to overlap a side panel, 55 a frame having a form adapted to be insert-

ed in said container, a pair of arms tiltable and movable substantially longitudinally in said frame, laterally projecting plates on said arms adapted to engage said flaps, means for tilting said arms to fold said flaps 70 upon said panel and means for actuating said arms longitudinally to press said flaps upon said panel.

2. In a machine for sealing containers having flaps, a frame adapted to support 75 said container, a pair of arms pivoted and movable substantially longitudinally in said frame, plates on said arms having plain surfaces adapted to engage said flaps, means for pivoting said arms to fold said flaps upon 80 said container and means for actuating said arms longitudinally to press said flaps upon said panel.

3. In a machine for sealing a container having a pair of oppositely disposed flaps 85 adapted to overlap a side panel, a frame adapted to support said container, a pair of arms pivoted and movable substantially longitudinally in said frame, laterally projecting plates on said arms adapted to engage 90 said flaps, plain surfaces formed on said arms to engage opposite sides of a container on said support, and means for actuating said arms longitudinally to press said flaps upon said panel with said plates. 95

4. In a machine for sealing a container having a plurality of flaps adapted to overlap a side panel of the container, a rigid support for the container, a plurality of arms tiltable toward and away from a container on said support, clamping plates on said arms adapted to engage said flaps, a lever adapted to be manipulated to move said arms toward the container, and means for clamping said plates upon said flaps to 100 seal said flaps upon said panel. 105

5. In a machine for sealing a container having a plurality of flaps adapted to overlap a side panel of the container, a form 110 adapted to fit within the container, a plurality of arms tiltable toward and away from a container on said form, clamping plates arranged on said arms to engage said flaps, squaring surfaces adjacent to said plates on said arms adapted to engage the lateral surfaces of a container on said form, means for tilting said arms to press said surfaces against the container, and means for clamping said plates upon said flaps to maintain 115 said flaps in engagement with said panel. 120

6. In a machine for sealing a rectangular container having a plurality of flaps adapted to overlap a side panel, a rigid support for the container, a pair of arms tiltable toward and away from opposite sides of a container on said support, clamping plates on said arms adapted to engage said flaps, squaring surfaces substantially perpendicular to said plates on said arms adapted to engage the latter surfaces of a container on said sup- 125-130

port, a lever adapted to be manipulated to tilt said arms and thereby press said surfaces against the container, and a movable support for said arms, arranged to be actuated by said lever to clamp said plates upon said flaps to secure said flaps upon said panel.

7. In a machine for sealing a container having a plurality of flaps adapted to overlap a side panel, a rigid support for the container, a plurality of arms tiltable toward and away from a container on said support, a slidable support for said arms, clamping plates on said arms adapted to engage said flaps, a lever adapted to be manipulated to tilt said arms toward the container, and means operable by said lever for moving said slidable support to clamp said plates upon said flaps.

20 8. In a machine for sealing a container having a plurality of flaps adapted to overlap a side panel, a rigid, substantially horizontal support for the container, a plurality of substantially upright arms tiltable toward 25 and away from a container on said support, laterally projecting clamping plates on said arms adapted to engage said flaps, a lever adapted to be manipulated to tilt said arms into engagement with the container, and 30 means for drawing said arms downward to clamp said plates upon said flaps.

9. In a machine for sealing a container having a pair of oppositely disposed flaps adapted to overlap a panel, a table arranged 35 to support said panel in horizontal position, said table being formed with apertures adjacent to opposite sides of a container supported thereby, a pair of arms pivoted be-

neath said table and extending upward through said apertures, substantially horizontal plates arranged on the upper ends of said arms to engage said flaps, a vertically movable support for said arms, a slide movable on said support to impart pivotal movement to said arms, a lever adapted to be manipulated to operate said slide and to draw said support downward and thereby clamp said plates upon said flaps, and resilient means for raising said support and lever.

10. In a machine for sealing a container having a pair of oppositely disposed flaps adapted to overlap a panel, a table, a form adapted to fit within said container and arranged to support said panel in horizontal position, said table being formed with apertures adjacent to opposite sides of said form, a pair of arms pivoted beneath said table and extending upward through said apertures, substantially horizontal plates arranged on the upper ends of said arms to engage said flaps, substantially vertical surfaces disposed on said arms to strike the sides of said container, a vertically movable support for said arms, a slide movable on 60 said support to impart pivotal movement to said arms, a lever adapted to be manipulated to operate said slide and to draw said support downward and thereby clamp said plates upon said flaps and square the container with said vertical surfaces and resilient means for raising said support and lever.

In testimony whereof, I have hereunto signed my name to this specification.

CHARLES C. GAMM.
